(57) **CLAIM**

The ornamental design for a mobile phone mount, as shown and described.

DESCRIPTION

FIG. 1 is a front, left, top perspective view of a mobile phone mount, showing my new design;

FIG. 2 is a rear, right, bottom perspective view thereof;

FIG. 3 is a rear, right, bottom perspective view of the mobile phone mount in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof, shown in a reduced scale; and,

FIG. 9 is a bottom plan view thereof, shown in a reduced scale.

The dashed broken lines in the figures illustrate portions of the mobile phone mount that form no part of the claimed design.

The short-short-long dashed broken lines shown in FIG. 1 represent the boundaries of the design and form no part of the claimed design.

1 Claim, 9 Drawing Sheets
